UNITED STATES PATENT OFFICE.

HAROLD S. ROYSE, OF MINNEAPOLIS, MINNESOTA.

MONEY SAFE.

Application filed September 21, 1921. Serial No. 502,096.

To all whom it may concern:

Be it known that I, HAROLD S. ROYSE, a citizen of the United States, residing at Minneapolis, in the county of Hennepin and State of Minnesota, have invented certain new and useful Improvements in Money Safes, of which the following is a specification.

My invention relates to money safes. It relates particularly to money safes into which the possessor may drop loose change from time to time until a sufficient amount has accumulated for deposit in a bank, which ordinarily would be the bank which puts out the money safe. An object is to provide a safe of this kind having a box portion for containing the money which may be readily cast from suitable material such as aluminum composition. Another object is to provide detachable booklike covers for the box portion which, when attached and the edges of the box are lacquered in gold or gilded, gives the safe the appearance of a book. The safe is thus given an attractive appearance and is convenient for carrying, since it may be easily slipped into the pocket or into a handbag. Another object is to provide the safe with a pocket for containing the passbook. Another object is to provide a register by means of which the possessor may keep a record of the amount of money which has been placed in the bank. Another object is to provide an unlocking device for the device by means of which the safe is locked, the two devices being so co-ordinated that the possessor of the safe or any unauthorized person cannot remove coins but when the safe is taken to the bank, the teller who has the unlocking device in his possession may quickly open the safe.

The full objects and advantages of my invention will appear in connection with the detailed description, and the novel features embodied in my inventive idea will be particularly pointed out in the claims.

In the accompanying drawings which illustrate a desirable embodiment of my invention,

Fig. 1 is a plan view of the upper edge of my safe. Fig. 2 is an elevational view showing one of the booklike covers opened. Fig. 3 is an enlarged view in central section. Fig. 4 is a view in section on the line 4—4 of Fig. 3, the book covers having been removed. Fig. 5 is a view in section on the line 5—5 of Fig. 7. Fig. 6 is a fragmentary view

similar to Fig. 4 but showing the unlocking device in a different position. Fig. 7 is a view in section on the line 7—7 of Fig. 4. Fig. 8 is a view similar to Fig. 7 showing the unlocking device in a different position. Fig. 9 is a view in section on the line 9—9 of Fig. 4.

Referring to the construction shown in the drawings, the numeral 10 designates in general a box which is preferably made of a combination of aluminum and other metal so as to be of lightweight and not liable to rust or tarnish. This box is preferably cast in one piece with the exception of a closure 12 hinged at one end as indicated at 14 in Fig. 3. This closure is provided with a slot 16 for the insertion of money, the removal of which through the slot is prevented by a plurality of pairs of guard fingers 18 extending inwardly from the closure and surrounded by a flange 20 as best shown in Fig. 9. The movable end of the closure is provided with a catch 22 normally pressed forward by a spring 24, the forward end of the catch being bent as best shown in Fig. 3 to engage under the lug 26 which is on the inside of the box. For operating this catch, I provide an unlocking device comprising a base member 28 having its lower portion cut away in angular shape so as to fit into an angular opening 30 in the closure. A small rod 32 is slidably carried by the base 28, this rod having a head 34 at its upper end. A coiled spring 36 is placed between the head 34 and the base, and the lower portion of the rod is bent so as to have an upwardly extending end 38 which is normally held within a recess in the base member as shown in Fig. 8 which is the position occupied when the unlocking device is inserted in the opening 30. The catch 22 is provided with a notch 40 adapted to receive the end 38 when the rod 32 is pushed down and turned, the downward pressure on the rod being released so that the tension of the spring 36 causes the end 38 to be drawn upwardly for engagement with the notch. Upon continuing the turning movement of the rod 32 in the direction indicated in Fig. 5, the catch is withdrawn as shown in Fig. 6, and the closure may be quickly opened by the teller who has the unlocking device in his possession. The back of the box 10, as shown in Fig. 1, is rounded in the manner of the back of a book, and is provided with a plurality of holes adapted to receive studs 42 project-

ing inwardly from the back 44 of the book-like covers 46 and 48 which are formed of suitable material such as leather or other flexible material. By means of this stud attachment, the covers may be readily removed when worn or soiled and replaced by new covers. One or more sheets of paper such as indicated at 50 may be secured at the middle of the sheet by the studs 42 passing through holes therein. These sheets may be used for advertising matter, and if desired, may be in the form of little booklets for conveying information to depositors, or persons who may later become depositors, of the different services rendered by the bank. These sheets or booklets are firmly held in place by the studs 42 and may be changed from time to time as the customer brings in the safe to have the contents thereof placed to his credit. In Fig. 2 the sheets 50 are shown partly torn away in order to disclose a pocket 52 with which the cover is provided on its inner side for holding a passbook. The passbook is thus prevented from being mislaid and the depositor always has his book when his safe is brought into the bank. As shown in Fig. 2 one face of the box is provided with a register which consists of two rotatable disks 54 for indicating dollars and two rotatable disks 56 for indicating cents. These disks are preferably mounted in a depression formed in the face of the box. By properly turning these disks, every time money is dropped into the safe a person is able to tell at a glance the exact amount of money contained therein.

The advantages of my invention have to a large extent been set forth in the foregoing description. The provision of the detachable cover has three principal advantages: First: It allows the banker a medium of advertising that is of great value as it permits him to slip in a little booklet as often as he wishes telling the advantages of a safety deposit box, a checking account, a trust account, and last but not least different plans for saving and investments. He can advertise the bank's securities and in fact, tell every savings customer about the different departments of the bank.

Second: If a customer has been using a money safe for a considerable time and closes out his account and returns the safe, a new and bright cover can immediately be attached at a cost of only a few cents, whereas if the cover were permanently attached to the safe, the depreciation in a few years from safes turned in on closed accounts would be a considerable item.

Third: The cover is made in such way that a pocket is provided for the pass book, thereby preventing loss of the same and the customer always has this book with him when the safe is brought in. The provision of the register in addition to enabling the cus-

tomer to keep accurate account of the money in the safe also acts as a check for the teller. When the safe is brought in the teller checks his account against the figures on the register and if they agree he may be sure that his account is correct. A depositor who has been dropping small coins into a money safe for a number of days or weeks is very apt to imagine that he has a great deal more in the safe than is actually there, and a great many times there is a doubt that the teller might have made a mistake in counting. This is entirely eliminated by the use of the register. The safe is provided with locking means which cannot be readily picked and the position of which is hidden. The particular unlocking device enables the teller to quickly open the safe when it is brought in, but the arrangement is of such character and operates in such manner that the safe cannot be opened by a key of the customary construction.

I claim:

1. A money safe comprising a boxlike member, booklike covers for said member, and means for detachably securing said covers to the back of said member. 90

2. A money safe comprising a boxlike member, the back of which is rounded in the manner of a book, booklike covers for said member, and means for detachably securing said covers to said rounded back. 95

3. A money safe comprising a boxlike member, booklike covers for said member, and interengaging means carried by the back of said member and by the back of said covers for detachably securing the latter. 100

4. A money safe comprising a boxlike member, booklike covers for said member, the back of said member being provided with holes, and studs carried by the back of said covers for detachably engaging in said holes. 105

5. A money safe comprising a boxlike member, the back of which is rounded in the manner of a book and is provided with holes, booklike covers for said member, and studs carried by the back of said covers for detachably engaging in said holes. 110

6. A money safe comprising a boxlike member, booklike covers for said member, a passbook pocket carried by said covers, and means for detachably securing said covers to said member. 115

7. A money safe comprising a boxlike member, booklike covers for said member, means for detachably securing said covers to the back of said member, and removable advertising sheets held in place by said means. 120

8. A money safe comprising a boxlike member, booklike covers for said member, the back of said member being provided with holes, studs carried by the back of said member, and removable advertising sheets held in place by said studs. 125

9. A money safe comprising a boxlike member, a closure for said member, said closure having an angular opening, a catch for locking said closure, and an angular unlocking device adapted to fit said angular opening for cooperation with said catch. 25
10. A money safe comprising a boxlike member, a closure for said member, said closure having an angular opening, a spring-pressed catch for locking said closure, an angular member adapted to fit said angular opening, a rod slidably and rotatably carried by said angular member, a head secured to the upper end of said rod, and a spring engaging said head for normally holding said rod raised, the lower portion 30 of said rod being bent to form an upwardly extending end adapted to be maintained by said spring in a recess in said angular member and said catch having a recess adapted to be engaged by said upwardly extending 35 end for retracting said catch when said rod is slid and rotated.
11. A money safe comprising a boxlike member, a closure for said member, said closure having an angular opening, a spring-pressed catch for locking said closure, an angular member adapted to fit said angular opening, and a rod slidably and rotatably carried by said angular member, the inner portion of said rod being bent so as 40
